CLAIM

The ornamental design for a christmas light clip, as shown and described.

DESCRIPTION

FIG. 1 is a perspective view of a christmas light clip showing my new design;

FIG. 2 is a top plan view thereof;

FIG. 3 is a bottom plan view thereof;

FIG. 4 is a side elevation view, the opposite side being a mirror image thereof;

FIG. 5 is an end elevation view as seen from the left in FIG. 1; and,

FIG. 6 is an end elevation view as seen from the right in FIG. 1.
